(57) **CLAIM**

The ornamental design for an assembly part for glove packaging equipment, as shown and described.

DESCRIPTION

FIG. 1 is a top perspective view of an assembly part for glove packaging equipment;

FIG. 2 is a top plan view thereof;

FIG. 3 is a bottom plan view thereof;

FIG. 4 is a left side view thereof;

FIG. 5 is a right side view thereof;

FIG. 6 is a front perspective view thereof; and,

FIG. 7 is a rear perspective view thereof.
